UNITED STATES PATENT OFFICE.

BERTRAM JOSEPH PYE AND HENRY RABBES, OF OAKLAND, CALIFORNIA.

FUEL-VAPORIZER.

1,310,873.

Specification of Letters Patent. Patented July 22, 1919.

Application filed August 21, 1918. Serial No. 250,812.

To all whom it may concern:

Be it known that we, BERTRAM J. PYE and HENRY RABBES, citizens of the United States, and residents of Oakland, in the county of Alameda and State of California, have invented certain new and useful Improvements in Fuel-Vaporizers, of which the following is a specification.

Our invention is an improvement in fuel vaporizers, and has for its object to provide a device of the character specified especially adapted for use with internal combustion engines, to be arranged between the carbureter and the intake manifold, for thoroughly breaking up and volatilizing the fuel.

In the drawings:

Figure 1 is a front view of the improved vaporizer;

20 Fig. 2 is a rear view;

Fig. 3 is a front view, with the fan and one of the housing rings removed;

Fig. 4 is a transverse section;

25 Fig. 5 is an enlarged detail of a portion of Fig. 4.

In the present embodiment of the invention a suitable support is provided, consisting of a pair of rings 1 and 2, each of which is provided at diametrically opposite points 30 with radial lugs 3, and the disks are connected in spaced and insulating relation by means of binding posts 7, a washer 4 of insulating material being arranged between the rings. One of the binding posts 7 is 35 electrically connected to the ring 1, and insulated from the ring 2, while the other post is insulated from the ring 1 and electrically connected to the ring 2. Each ring has a diametrically extending cross bar 5 and 6, 40 respectively, and the lugs 3 and the cross bars are so arranged that when the lugs 3 of the two rings are superposed the cross bars 5 and 6 will be at right angles to each other, as shown.

45 A set screw or binding post 10 is connected with the cross bar 5, and a similar screw 11 connects the cross bars 5 and 6 at their intersection, the set screw 11 being insulated from the cross bar 5 and electrically connected with the cross bar 6. A resistance wire 9 is arranged helically within the rings, one end of the said wire being connected to the set screw 10, while the other is connected to the set screw 11 and this will

55 forms an electrical connection between the said set screws and between the rings 1 and 2. The terminals of an electrical circuit (not shown) are connected with the binding posts 7, and it will be evident that when the circuit is not interrupted, the current will 60 flow from the positive pole of the source of supply to the binding post 7, for instance, at the left of Fig. 4, from the said post to the ring 1, and by way of the set screw 10, the wire 9 and the set screw 11 to the 65 ring 2, and from the ring 2 by way of the binding post 7 to the source of supply.

A fan 12 is supported by the set screw 11, and it will be noticed that the blades of the fan are provided with numerous perforations. A sleeve 13 is connected with the set screw 11 on the opposite side of the disks from the coil, and the set screw 14 which connects the fan 12 with the sleeve engages this sleeve. It will be noted that while the 75 sleeve 13 is connected with the set screw 11, the said sleeve is also insulated from the cross bar 5.

Housing rings 15 are arranged on the opposite faces of the supporting frame, the 80 said rings being of insulating material and of the same diameter as the rings 1 and 2.

In use, the improved volatilizer is arranged, as before stated, between the carbureter and the intake manifold in such 85 manner that the fuel passing from the carbureter to the manifold passes through the openings of the rings, in contact with the heated wire 9. The suction of the engine will rotate the fan, which will thoroughly 90 break up and volatilize the fuel, while at the same time the fuel is heated by the coil. Any suitable source of electrical energy may be connected with the binding posts.

We claim:

1. A heater and volatilizer for internal combustion engines adapted to be arranged between the carbureter and the intake manifold and comprising a suitable support having an opening for registering with the 100 opening of the manifold, an electrical heater on the support at the opening, a rotatable element carried by the support and adapted to be rotated by the passage of the fuel, said support consisting of spaced insulated rigidly connected rings, said rings having diametrically arranged cross bars extending at approximately right angles to each other,

and the heater having a coil connected at its ends to the cross bars.

2. A heater and volatilizer for internal combustion engines adapted to be arranged between the carburetor and the intake manifold and comprising a suitable support having an opening for registering with the

opening of the manifold, an electrical heater on the support at the opening, and a rotatable element carried by the support and adapted to be rotated by the passage of the fuel.

BERTRAM JOSEPH PYE.
HENRY RABBES.
